Patented Feb. 17, 1959

184,428

BASEBALL SAFETY HELMET

Lawrence Finkelhor, University Heights, Ohio
Application October 24, 1957, Serial No. 48,223

Term of patent 14 years

(Cl. D3—13)

Fig. 1

Fig. 2

Fig. 3

Fig. 4

Fig. 1 is a side elevational view of a baseball safety helmet showing my new design.

Fig. 2 is a top plan view thereof.

Fig. 3 is a front elevational view; and

Fig. 4 is a rear elevational view thereof.

I claim:

The ornamental design for a baseball safety helmet, substantially as shown.
